(57) **CLAIM**

The ornamental design for a watch winder, as shown and described.

DESCRIPTION

FIG. 1 is a front perspective view of a watch winder;
FIG. 2 is a front elevation view thereof;
FIG. 3 is a rear elevation view thereof;
FIG. 4 is a left side elevation view thereof, with the right side
being a mirror image thereof;
FIG. 5 is a top plan view thereof; and,
FIG. 6 is a bottom plan view thereof.
The broken line showing of the watch winder is for the
purpose of illustrating portions of the watch winder and
forms no part of the claimed design.

1 Claim, 6 Drawing Sheets
